TUBULAR BANDAGE

Benjamin Rosenfield, New York, N. Y., assignor
to The Scholl Mfg. Co., Inc., New York, N. Y.,
a corporation of New York

Application August 6, 1949, Serial No. 108,986

4 Claims. (Cl. 128—157)

1

This invention relates to improvements in a tubular bandage applicable to extremities of the human body and particularly to the digital members of the body. It may be employed on animals as well as humans, however, and adapted to other analogous uses.

It has been found that previous methods of bandaging the human body involving the use of tubular bandages, while fairly satisfactory when used by skilled physicians or nurses, do not always prove satisfactory where the patient wishes to bandage himself, and this is true especially where a finger is involved and one hand is wholly or partly disabled.

One of the objects of the present invention is to provide a method of applying a tubular bandage whereby the same may be easily accomplished by the operator or user and with the use of only one hand if necessary.

Another object of this invention is to provide a tight, smooth and secure closure at the outer end of a bandage whereby lumps and knots and an uncomfortable or irritating bandage are avoided, since these bulky closures often result in injury to the affected member especially if the injury or surgery is at the end of a finger or toe.

Other uses and advantages will be apparent from the following specification and the accompanying drawings referred to therein, in which:

Fig. 1 is a side view of a tubular bandage closed at its central portion according to the invention;

Fig. 2 is a side view of an applicator used in the practice of the invention;

Fig. 3 is a longitudinal cross section of an applicator and tubular bandage in position for insertion of a finger or toe therein or for passing the former over the latter;

Fig. 4 is a horizontal cross section of the bandage and applicator after insertion of a digit member therein and application of the bandage thereto.

Referring to Fig. 1 of the drawings, 1 and 1a represent a piece of tubular gauze or stall which is closed and tied in the middle as at 2. The closure element consists of a short length of cord, thread or surgical suture coated and impregnated with a resinous or other tacky waxlike semi-fluid substance which will cause it to adhere to itself and to the fabric of the tube when wrapped around it and not dry out even after considerable exposure. Some of the semi-fluid substances which may be used for example, are beeswax, refined shoemaker's wax, turpentine in a pasty state, any of the numerous sticky resins

or a combination of any of these. The purpose of using an adhesively coated thread or string is that it may be wrapped tightly around the tubular gauze and will close and maintain closed the gauze without the necessity of tieing and will hold the tube closed tightly and permanently, an ordinary thread or cord may be used, however, and tied in the usual manner, but with less satisfactory results, particularly if one hand of the user is wholly or partly disabled. The wrapping operation is also superior to twisting or tieing because it makes a smooth closure without the objectionable lump or knot.

Referring to Fig. 2, the applicator used in the practice of this invention consists preferably of a piece of sheet metal or plastic stamped or molded into an elongated U-shaped channel-bar 3, with open flared and rounded ends at 3a and doubled on itself at 4 to form a semi tube, the bent over portion 4 forming a handle and spring connecting portion 5 cut away as at 6, this cut away portion is advisable to prevent crimping of the metal when the bend 4 is made. As the arms or forks of the applicator are spaced apart and the instrument is made of resilient material it is both contractile and expansible and therefore will contract under the constriction of the tubular gauze which is of lesser diameter, when it is applied thereto, and expand when it is removed therefrom.

In operation a piece of gauze of proper length—usually about twice the length of the body member—is selected and the adhesive string 2 wrapped around its middle so that the closed tubes 1 and 1a are of approximately equal length. The tube portion 1a is now slipped over the outside of the channel bars or fingers 3 until the flared ends 3a encounter the closure 2. The tube portion 1 is now retroverted or folded over the closed tube portion 1a as shown in Fig. 3. The digital member to be bandaged is now pushed into the interior of the applicator, or the applicator passed over it open end first, as shown in Fig. 4, thus automatically reversing the positions 40 of the closed tubular bandage members 1 and 1a, stripping them from the applicator and causing them to surround the digit member. The applicator expands to its normal diameter when released from the tubular bandage and may then be slipped off the digit member and bandage, now inside it, and the bandaging has been completed.

Variations in the details of construction and operation above described may be made without departing from the scope of the invention. No

claim is made to the applicator or the tubular bandage per se and they may have any suitable form, either that of copending application of Scholl Serial No. 749,754, filed May 22, 1947 now patent No. 2,522,842, or Hendrickson, et al patent, No. 2,456,507 of December 14, 1948, both owned by the owner of the present application, or other satisfactory form, and they may be employed within the scope of the appended method or process claims.

One of the advantages of the present method is that it enables the physician or chiropodist to mount a number of tubular bandages on applicators and have them on hand ready for immediate application to an extremity of the body and without being touched by the hands, by simply grasping the loop or handle and passing it open end first over the affected portion of the body, and thus expediting the operation and preserving the aseptic condition of the bandage if desired.

What I claim is:

1. A combined multiple tubular bandage and applicator therefor comprising a longitudinally divided resilient, hollow applicator of sheet material having an open end and a closed end, a piece of tubular fabric closed medially and having the portions on both sides of the closure passed over the applicator with the closure at the open end of the applicator and closing it, whereby said tubular fabric may be applied to an extremity of the body by passing said extremity into the said open end and through the interior of the applicator thus stripping the bandage off the applicator and applying it to the said extremity.

2. A combined multiple tubular bandage and

applicator therefor comprising a longitudinally divided resilient, hollow applicator of sheet material having an open end and a closed end, a piece of tubular fabric closed medially and having the portions on both sides of the closure passed over the applicator and holding it in contracted position with the closure at the open end of the applicator and closing it, whereby said tubular fabric may be applied to an extremity of the body by passing said extremity into the said open end of and through the interior of the applicator thus stripping the bandage off the applicator and applying it to the said extremity.

3. In a combined bandage and applicator as specified in claim 1, the medial closure of the tubular fabric comprising a piece of adhesive cord or the like wrapped around the tube and drawn tight to close it but without tieing, whereby a secure closure is provided without forming a lump or knot.

4. In a combined bandage and applicator as specified in claim 1, the medial closure of the tubular fabric comprising a piece of cord or the like wrapped around the tube and drawn tight to close it, whereby a secure closure is provided without forming a lump or knot of fabric.

BENJAMIN ROSENFIELD.
